UNITED STATES PATENT OFFICE.

WILLIE BURCH, OF LOWELL, MICHIGAN.

DEVICE FOR SEALING FRUIT-JARS.

SPECIFICATION forming part of Letters Patent No. 660,092, dated October 23, 1900.

Application filed July 15, 1899. Serial No. 723,971. (No model.)

To all whom it may concern:

Be it known that I, WILLIE BURCH, a citizen of the United States, residing at Lowell, in the county of Kent and State of Michigan, have 5 invented a new and useful Device for Sealing Fruit-Jars, of which the following is a specification.

My invention relates to jar and bottle closures; and the object thereof is to provide a 10 device of the character described which is adapted to hermetically seal any vessel—such as a jar, bottle, or can—but more particularly milk or preserve jars and glass bottles.

With this object in view my invention consists of a vessel, preferably of glass, on either side of which is located a segmental projection having a groove therein, the top edge of the vessel being flat to receive a packing-ring, and a flanged cap on the packing-ring, a screw- 20 actuated locking-plate above the cap having two oppositely-disposed engaging bails designed to operatively connect with the segmental projections on the side of the vessel.

My invention further consists in certain 25 details of construction, all of which will be fully described in the following description, recited in the claims, and illustrated in the drawings, in which—

Figure 1 is a perspective view of a glass jar 30 constructed in accordance with my invention. Fig. 2 is a vertical longitudinal section therethrough. Fig. 3 is a perspective view of a bottle, showing the cap of a modified construction; and Fig. 4 is a section through the 35 same.

Referring now to the drawings by reference-numerals, 5 indicates the jar or bottle, preferably made of glass and provided with the usual restricted neck, the top edge of 40 which it is designed to cast or mold perfectly square; but in the process of manufacture the surface of this edge is sometimes unequal, but, as will later appear, I have provided for any inequality which may occur.

45 At a suitable point below the top of the jar or bottle and diametrically opposite are two semicircular or segmental ears 6, provided with the peripheral grooves 7.

8 indicates a packing ring or disk of suitable 50 resilient material, such as rubber or cork, positioned upon the top edge of the neck and held thereon by the cap 9. In a jar construc-

tion this cap will be slightly different than when used on a bottle. For instance, the jar will be provided with a cap having an outwardly-projecting flange 10, designed to rest upon the top of the packing-ring, and the downwardly-extending flange 11, designed to extend into the neck of the jar, and thus form a right-angular groove 12, into which the inner edge of the packing-ring will fit snugly and when the cap is pressed firmly down an air-tight joint will be formed. In a bottle the cap 9 will be provided with the downwardly-projecting flange 10^a, which will fit over the 65 packing-disk and neck, as shown in Fig. 4. On top of this jar-cap is an annular groove 13, in which the edges of a locking-plate 14 will normally rest.

15 represents radially-extending eye-carry- 70 ing lugs or projections on the top of the locking-plate, which may be cast thereon or struck from the metal with a suitable die if the same is made of sheet metal, and said lugs or projections are arranged in oppositely-disposed 75 pairs. Hingedly connected to each pair of the lugs or projections 15 is a bail-like loop 16, and said loops engage the grooves of the ears 6. Into the central threaded perforation of the locking-plate is then inserted a screw 17, 80 which will have any kind of a suitable head, so that when the same is turned the cap will be forced down on the packing-ring as tightly as desired, and any inequality of the upper edge of the jar will be taken up by the packing- 85 ring heretofore referred to.

While I have described the very best means at my command for accomplishing the desired result, I do not abandon the right to make such slight changes and alterations as would 90 properly come within the scope of my invention without departing from the spirit thereof.

Having thus fully described my invention, what I claim as new, and desire to secure by Letters Patent of the United States, is— 95

1. In a closure of the class described, the combination with a vessel provided at its sides with oppositely - arranged ears, of a cover, a locking-plate arranged above said cover, said plate being provided with radially-extending lugs or projections arranged in oppositely-disposed pairs, a locking-bail hingedly connected to each pair of said lugs or projections and adapted to engage the ears 100

at the sides of the vessel, and a screw carried by the locking-plate and bearing against the cover of the vessel for binding the said locking-bails in engagement with said ears.

- 5 2. In a closure of the class described, the combination with a jar provided with oppositely-arranged ears, of a cover provided with an annular groove, a locking-plate arranged above said cover, and having its edges fitting in the groove thereof, locking-bails carried

by said plate and adapted to engage the ears of the jar, and a screw also carried by the locking-plate, and bearing against the cover for binding the locking-bails in engagement with said ears.

WILLIE BURCH.
